PLUMB BOB

Adam Johnston McLaws, Jacksonville, Fla., assignor of one-fourth to Elmore Cohen, West Palm Beach, Fla.

Application December 4, 1930, Serial No. 499,998

5 Claims. (Cl. 33—216)

My invention relates to plumb bobs for use by surveyors, carpenters, mechanics, masons, marble setters and all other crafts.

The primary object of my invention is the provision of a plumb bob with a nonrigid point, in which the tip of the bob is so operated as to be withdrawn from the body of the bob by means of the weight of the body upon the plumb line when the bob is in actual use, and recoiling into the body of the bob by means of a spring when the plumb line is free of tension, thereby protecting and greatly lengthening the life of the point of the bob.

Another object of my invention is the provision of a plumb bob consisting of a minimum of parts, any of which can be replaced quickly and at slight cost.

A further object of my invention is the provision of a type of bob that may be increased or decreased in weight, or varied in shape, thereby making its use more universal.

With the foregoing and other objects in view, my invention consists in the construction, combination and arrangement of parts, as are hereinafter more fully described and illustrated in the attached drawing.

One form of the invention is illustrated in the accompanying drawing, in which Figure 1 is an elevation of the tool. Figure 2 is a vertical cross section showing all parts. Plumb line 1 passes down through cap 2, said cap being secured to a body member 3 by threads 8. The line then passes slidably through eyelet 6 which is positioned below the upper end of pin 4, then over the head of pin 4, through a slot 9 in the head of the pin 4. The end of the line 1 is made fast to the eyelet 5 that is fixed to body member 3 below the slot 9 and on the side of pin 4 opposite that on which eyelet 6 is positioned.

Pin 4 slidably passes through the body of the bob 3 and forms a point for the bob. Spring 7 holds the pin 4 retracted until the weight of the entire tool is hanging on plumb line 1. When the bob is thus suspended by the line, its weight being greater than the resistance of the spring, the point is projected from the body of the bob and is exposed. As soon as the weight is taken off the plumb line 1, spring 7 forces the pin 4 upwards and protects the point of the pin 4.

Having thus described my invention, I make the following claims:

1. The combination, in a plumb bob of an apertured hollow body with two eyelets therein, a removable threaded cap, a pin movable to project from the body through the aperture and having

a slotted head and a spring that fits around said pin.

2. The combination, in a plumb bob, of an apertured hollow body with two eyelets therein, a removable threaded cap, having a hole therethrough, a pin movable to project from the body through the aperture and having a slotted head, together with spring that fits around said pin and a cord or plumb line attached to one of the eyelets, extending over the pin through slot in the head thereof, thence slidably through other eyelet and protruding through the hole in the cap.

3. The combination in a plumb bob of an apertured hollow body and a hollow threaded cap having an aperture to permit the passage of a plumb line, a slideable pin having a slotted head mounted in said hollow body adapted to project from the body through the aperture, a spring around said pin adapted to normally retain said pin within the body, eyelets on both sides of said pin, a plumb line secured to one of said eyelets and passing over the slotted head through the eyelet on the opposite side and through the aperture in the threaded cap, said pin adapted to be projected through the lower aperture when the body of the bob is suspended from the plumb line.

4. A plumb bob having an apertured hollow body, a removable threaded cap having an opening therethrough, a slideable pin adapted to project from the body, resilient means in cooperation with said pin adapted to normally hold said pin within said body, a plumb bob cord secured within said body and adapted to pass over the top of said pin, a second securing means within said body on the opposite side of said pin, said cord adapted to continue under said last mentioned securing means and up through said opening in said cap so that upon suspension said pin will be forced against resilient means through said aperture.

5. A plumb bob having an apertured hollow body and a cap apertured to permit the passage of a plumb bob cord, a slideable pin mounted in said body and adapted to project through the bottom of said body, resilient means normally holding said pin retracted, eyelets on both sides of said pin, said cord secured to one of said eyelets and extending across the top of said pin under the second eyelet and out through the aperture formed in the cap, said pin adapted to be projected through said opening in the bottom of said body upon the suspension of said plumb bob on said cord.

ADAM JOHNSTON McLAWS. 110
